UNITED STATES PATENT OFFICE.

ANNIE GOLTRY, OF NORTH PLATTE, NEBRASKA.

HOISTING APPARATUS.

1,374,444.

Specification of Letters Patent. Patented Apr. 12, 1921.

Application filed October 18, 1919. Serial No. 331,626.

To all whom it may concern:

Be it known that I, ANNIE GOLTRY, a citizen of the United States, residing at North Platte, in the county of Lincoln and 5 State of Nebraska, have invented certain new and useful Improvements in Hoisting Apparatus, of which the following is a specification.

My invention relates to hoisting apparatus and more particularly to that type of devices which may be effectively employed as a log jack for elevating logs whereby they may be sawed or otherwise treated.

An important object of my invention is to 15 provide a device including means whereby a load may be elevated and retained in said position.

Another important object of the invention 20 is to provide a device of this nature which includes means whereby the grapple may be automatically lowered from its elevated position.

Another object of the invention is to provide a device of the above nature including 25 means whereby the load is securely gripped and held in this manner while it is elevated.

A still further object of the invention is to provide a device of the above nature which is strong, durable, comparatively 30 inexpensive to manufacture, and is highly efficient in practice.

Other objects and advantages of the invention will become apparent during the course of the following description.

35 In the accompanying drawings:—

Figure 1 is a side elevation of the invention in use, parts of the same being broken away, and

Fig. 2 is an end elevation of the same.

40 In the drawings, wherein for the purpose of illustration is shown a preferred embodiment of the invention, the numeral 3 designates a frame in general, which consists of a pair of vertically arranged arched members 4, retained in spaced parallel relation by spacing elements 5, some of which consist of bolts while others are sleeves, the latter being mounted upon elements to be hereinafter described. The lower ends 6 of 45 the arched members 4 are extended outwardly of the members to be connected by bars 7.

A lever 8, substantially ogee in configuration is pivotally mounted adjacent its inner 55 end, upon a shaft or bolt 9, and is retained in spaced relation between the arched mem-

bers 4 by spacing elements 5. As will be seen in Fig. 2 of the drawing, this lever is mounted upon the shaft 9 adjacent one of the arched members 4 whereby the operating 60 mechanism for the lever may be disposed adjacent the co-acting arched member, as more clearly shown in Fig. 2 to permit efficient operation of the various parts of the invention.

65 A grapple or lazy-tongs 10 is employed to grip the load, and the upper ends of the lazy-tongs are connected with the inner end of the lever 8 through the medium of links 11, whereby a firm grip is obtained upon the 70 load by the lazy-tongs to prevent accidental dislocation.

The outer end of the lever 8 extends a substantial distance beyond the frame 3 to be connected at its outermost end with a cable 75 12, which is wound and secured upon a drum 13 journaled upon a shaft 14, which connects the lower end of the arched members 4 upon one side of the frame. A sprocket wheel 15 is secured to the drum 13 adjacent one of 80 the arched members 4 and meshes with a smaller sprocket wheel 16 secured to a shaft 17 mounted transversely through the arched members the proper distance above the shaft 14. Each face of the sprocket wheel 16 is 85 equipped with a disk 18 of the same diameter as the sprocket wheel, whereby these disks prevent disengagement of the sprocket wheel 16 with the wheel 15. As is customary, the spacing elements 5 are mounted 90 upon the shaft 17 upon each side of the sprocket wheel 16 whereby it is retained in its proper position to effectively engage its co-acting sprocket wheel. The shaft 17 is equipped with a crank 19 to permit the 95 operator to easily operate the lever operating mechanism. A gravity pawl 20 is pivotally mounted upon a bracket 21 secured to the frame directly above the sprocket wheel 16 whereby the working end of the pawl 20 100 normally engages the teeth of the sprocket wheel 16. This pawl 20 prevents retrograde movement of the sprocket wheel 16 but when it is desired to permit such movement of the sprocket wheel 16 the handle 22 of the pawl 105 is engaged, which action disengages the working end of the pawl.

When the grapple is in an elevated position and it is desired to automatically return the same to the ground for engagement with 110 the load, the pawl 20 is disengaged from the sprocket wheel 16 to permit reaction of

a coiled spring 23 having one end connected with the lever 8, a substantial distance beyond the frame, while the opposite end of the spring 23 is secured to an upstanding arm of bracket 24. This bracket is secured to the top of the frame 3 a substantial distance beyond the center of the lazy tongs, and it extends upwardly of the frame a substantial distance so that by connecting 10 one end of the spring 23 to the uppermost edge of this bracket, the spring will have a greater effect upon the lever 8 during the reaction of the spring.

In operation, it will be manifest that the 15 spring 23 normally retains the various parts of the invention in such position that the grapple or lazy-tongs 10 are always in a position to receive a load or log. Consequently the lazy-tongs are first adjusted to effectively grip the load, after which the crank 20 19 is actuated to impart a clockwise rotation to the sprocket wheel 16, which in turn imparts a counter clockwise movement to the larger sprocket wheel 15. As the drum 13 is 25 rotated with the sprocket wheel 15, it will be manifest that the cable 12 will be wound thereon and consequently the outermost end of the lever 8 will be moved downwardly causing its inner end to ascend and the coil 30 spring 23 to expand. Of course, the links 11 and lazy tongs 10 will be elevated together with the load, while the working end of the pawl 20 slips over the teeth of the sprocket wheel 16. When the load has been 35 elevated to the desired height, its descension is prevented by the pawl 20 engaging the sprocket wheel 16. However, after the load has been treated or the log sawed, the working end of the pawl 20 may be disengaged 40 from the sprocket wheel 16 thereby permitting ready reaction of the coil spring 23 and the pivotal movement of the lever 8 to return the grapple to the ground.

The foregoing description and accompanying drawings have reference to what 45

might be considered to be the approved or preferred form of my invention. I desire it to be understood that I may make such changes in the construction, combination and arrangement of parts, materials, dimensions, et cetera, as may prove expedient and fall within the scope of the appended claims.

Having thus fully described my invention what I claim as new and desire to secure by Letters Patent, is:-

1. A hoisting apparatus comprising a frame, a lever pivoted adjacent one end to the frame, grapple means connected to the end of the lever adjacent its fulcrum, means connected with the other end of the lever for actuating the same, and means for automatically lowering the grapple means.

2. A hoisting apparatus comprising a frame, a lever pivoted adjacent one end to the frame, grapple means connected to the end of the lever adjacent its fulcrum, means connected to the outer end of the lever for actuating the same, and a coiled spring having one end connected to the lever and its opposite end connected to the frame for automatically lowering the grapple.

3. A hoisting apparatus comprising a frame, a lever pivoted adjacent one end to the frame, grapple means connected to the end of the lever adjacent its fulcrum, means connected with the other end of the lever for actuating the same, an arm secured to the frame and projecting above the fulcrum of the lever, and a coiled spring having one end connected to the lever and its opposite end connected to the free end of said arm for automatically lowering the grapple.

In testimony whereof I affix my signature in presence of two witnesses.

ANNIE GOILTRY.
